(57) **CLAIM**

The ornamental design for an electrical connector keying arrangement, as shown and described.

DESCRIPTION

FIG. 1 is a perspective view of a first embodiment of my electrical connector keying arrangement in accordance with the invention;

FIG. 2 is an end view of the embodiment of my electrical connector keying arrangement illustrated in FIG. 1;

FIG. 3 is a side elevation view of the first embodiment of my electrical connector keying arrangement illustrated in FIG. 1;

FIG. 4 is a plan view of the first embodiment of my electrical connector keying arrangement illustrated in FIG. 1;

FIG. 5 is a perspective view of a second embodiment of my electrical connector keying arrangement in accordance with the invention;

FIG. 6 is an end view of the second embodiment of my electrical connector keying arrangement illustrated in FIG. 5;

FIG. 7 is a left-side elevation view of the second embodiment of my electrical connector keying arrangement illustrated in FIG. 5;

FIG. 8 is a plan view of the second embodiment of my electrical connector keying arrangement illustrated in FIG. 5;

FIG. 9 is a perspective view of a third embodiment of my electrical connector keying arrangement in accordance with the invention;

FIG. 10 is an end view of the third embodiment of my electrical connector keying arrangement illustrated in FIG. 9;

FIG. 11 is a left-side elevation view of the third embodiment of my electrical connector keying arrangement illustrated in FIG. 9; and,

FIG. 12 is a plan view of the third embodiment of my electrical connector keying arrangement illustrated in FIG. 9.

The broken lines illustrated in the accompanying drawings define the bounds of the claimed design.
